UNITED STATES PATENT OFFICE.

FREDERICK H. PERRY, OF BEVERLY, MASSACHUSETTS, ASSIGNOR TO UNITED SHOE MANUFACTURING COMPANY, OF PATERSON, NEW JERSEY, A CORPORATION OF NEW JERSEY.

FASTENING.

No. 890,447.

Specification of Letters Patent.

Patented June 9, 1908.

Application filed April 14, 1906. Serial No. 311,662.

To all whom it may concern:

Be it known that I, FREDERICK H. PERRY, a citizen of the United States, residing at Beverly, in the county of Essex and Commonwealth of Massachusetts, have invented certain improvements in Fastenings, of which the following description, in connection with the accompanying drawings, is a specification, like reference characters on the drawings indicating like parts in the several figures.

This invention relates to metallic fastenings, more particularly to screw-threaded fastenings, for securing together layers of material such, for example, as the outer-soles and innersoles of boots and shoes, and its object is to provide a fastening which will obviate disadvantages found to exist in similar fastenings used heretofore.

When securing the outer-soles of boots and shoes to their innersoles a screw-threaded fastening is desirable because it can be inserted without using an awl for forming an opening to receive it, and the threads give to it a greater holding power than is afforded by the smooth surface of a nail or peg. In this class of fastening the space between the ribs forming the threads is preferably considerably wider than the thickness of the threads so as to afford as much frictional resistance as possible to resist a torsional strain, and thus prevent a rotation of the fastening. In the screw-threaded fastenings heretofore made, this space has contributed but little to the holding capacity because the frictional resistance afforded by the mere rubbing of the smooth surface of the fastening against the stock into which it has been inserted is soon overcome. As a result, while the shoe is being worn, the fastening is practically free to rotate, on account of its screw-threaded formation, either upwardly above the inner surface of the innersole or downwardly beyond the tread face of the outer-sole. A displacement in either direction causes inconvenience to the person wearing the shoe.

The present invention obviates this objection by providing a screw-threaded fastening which will successfully resist a torsional strain and will, therefore, wear without displacement as the shoe sole wears. One means for accomplishing this is by utilizing the space or groove between the threads to

increase the holding power of the fastening. To this end the surface of the fastening between the ribs forming the threads is preferably roughened in such manner that as the fastening is inserted the depressions formed by reason of such roughening become filled with portions of the material being secured, whereby an efficient locking means is formed for thereafter holding the fastening against any tendency to rotate.

In the accompanying drawings, which illustrates the preferred form of the invention, Figure 1 shows a coil of the preferred form of sole-fastening wire to be placed in a machine adapted to insert and sever the same into proper lengths; Fig. 2 shows an enlarged view of a short section of said coil; Fig. 3 shows a cross-sectional view of Fig. 2; and Fig. 4 shows a severed fastening in position, securing together two layers of stock; Figs. 5 and 6 show modifications of the preferred form of wire.

Referring to the drawing, the fastenings are preferably made in the form of a wire having a body portion 10 of indefinite length, which may be conveniently coiled, as shown, for use in a machine for screwing one end of the coil through the outer sole and into the inner sole of a boot or shoe, conveniently arranged knives then severing the wire flush with the tread face of the outersole, or, if the sole is channeled, flush with the bottom of the channel.

The body portion 10 of the wire is here shown as provided with spirally-arranged parallel threads 12 and 14 which may be formed in any convenient manner, as by rolling a desired length of smooth wire between suitably formed roller dies. At the same time that the threads are formed or subsequently, as may be convenient, the spaces between the ribs forming the threads are provided with a series of depressions 16 which may be of any convenient configuration. These depressions are here shown as cup-shaped but preferably comparatively shallow, so that their edges form obtuse angles with the surface of the fastenings, and thus in no sense act as cutting or grinding edges for pulverizing the stock into which the wire is inserted. By reason of these depressions 16 the hitherto smooth surface between the threads is roughened to such an extent that after the wire has been inserted the fibers of the stock 18

are enabled to spring back from the position into which they have been forced, into the depressions, and, by filling them, form a locking means for preventing rotation of the wire, which consists of an integral portion of the stock projecting within the surface of the body portion of the fastening.

Although the depressions 16 alone materially increase the holding power of the fastening, an added advantage is gained by forming said depressions with a slight projection or nib 20 substantially in the center of each depression and extending outwardly, preferably not further than the surface of that portion of the wire in which the depressions are formed.

The results of tests made with fastenings embodying this invention have demonstrated that their capacity to resist a torsional strain has been largely increased over that of the double-thread wire with smooth grooves between the threads, such as has been generally used heretofore.

The wire is preferably given a double thread because such a formation enables the cutters of the inserting machine to sever the fastening without destroying the thread. The double thread also increases the holding power of the wire to some extent. It is obvious, however, that a single-thread wire provided with the roughened surface herein described would prove effective in overcoming a rotation of the fastening while the shoe is being worn.

It will be understood that the expressions in the claims, "between the turns of the rib," "surface between the ribs forming the threads" and "spaces between the threads" are not intended to refer to all of said surface or to each and every space, as it is obvious that the desired end may be gained to some degree by forming the depressions over a portion only of the surface named, for example, as illustrated by Fig. 5, or in alternate

spaces between the threads, when the double-threaded wire is used, as illustrated by Fig. 6.

Having described my invention, what I claim as new and desire to secure by Letters Patent of the United States, is:—

1. A screw-threaded fastening device comprising a body portion having upon it an uninterrupted smooth sided helical rib forming the thread, and having between the turns of the rib an interrupted face.

2. As a new article of manufacture, a screw wire having a series of depressions formed in that portion of its surface between the ribs forming the threads, each of said depressions having a nib or raised portion which projects from its surface.

3. As a new article of manufacture, a screw wire having a series of depressions formed in the surface of the spaces between the threads, each of said depressions having a nib or raised portion which projects from substantially the center of its surface and is of a height substantially equal to the depth of the depression.

4. A screw-threaded fastening device comprising a body portion having upon it a smooth sided continuous helical rib forming a thread, and having upon its surface between the turns of said thread a series of depressions, the edges of said depressions forming obtuse angles with the surface of said space, whereby when the device is inserted into stock the fibers thereof are merely forced aside and spring back into said depressions to form a locking means for preventing rotation of the device.

In testimony whereof I have signed my name to this specification in the presence of two subscribing witnesses.

FREDERICK H. PERRY.
